UNITED STATES PATENT OFFICE.

LEVI H. THOMAS, OF CHICAGO, ILLINOIS.

CUFF-BUTTON.

SPECIFICATION forming part of Letters Patent No. 243,996, dated July 5, 1881.

Application filed January 7, 1881. (No model.)

To all whom it may concern:

Be it known that I, LEVI H. THOMAS, a citizen of the United States, residing at Chicago, in the county of Cook and State of Illinois, 5 have invented certain new and useful Improvements in Cuff-Buttons; and I do hereby declare the following to be a full, clear, and exact description of the invention, such as will enable others skilled in the art to which it appertains 10 to make and use the same, reference being had to the accompanying drawings, and to the letters or figures of reference marked thereon, which form a part of this specification.

My invention relates to an improvement in 15 the sleeve and cuff button for which Letters Patent No. 233,299 were granted to me October 12, 1880; and it consists in the construction of parts whereby the button is securely held in place without the intervention of a 20 gripping-lug, as shown in said patent, while it is prevented from turning in the button-hole by a locking-lug, as hereinafter more fully described and claimed.

In the drawings, Figure 1 is a perspective 25 view of the button; Fig. 2, a plan of same; Fig. 3, an elevation of the button applied to a cuff or sleeve, the same being in section; Fig. 4, a plan of a modification; Fig. 5, a plan and elevation of a modification.

30 A represents the head of the button, which may be made of metal, ivory, or other suitable material. At the center of the head A rises the shank B, made in one piece, or not, with the head, as desired, and terminating in a 35 shoe, C, bent at right angles, or nearly so, to the shank, and extending beyond the shank at one side. This shoe I make, preferably, of the oval shape shown in Figs. 1 and 2; but it may be a flat straight bar, as shown in Fig. 4, or a 40 round plate, as in Fig. 5. A continuation of the shank B on its side opposite to the shoe C forms a lug, D, or a locking-projection on the head A. This lug extends at right angles to the shoe C, and is made in the shape shown in 45 Figs. 1 and 3, higher at its outer end than where it meets the shank, and tapering or wedge-shaped from the shank to its outer extremity, as seen in Fig. 1. The shoe C is not

located centrally with the shank B, but lies on one side of it, out of the way of the lug D, 50 which extends on the other side of the shank.

The lug D, as in Fig. 5, may be a separate projection on the head A, and not connected with or attached to the shank, as such a lug, in connection with the one-sided shoe, would 55 accomplish a similar purpose as if it were a continuation of the shank.

By my arrangement of the shoe on one side of the shank it is more easily inserted in the button-hole, and also has a greater holding-surface 60 on the cuff or sleeve than if placed centrally on the shank. The shoe is passed through the button-holes, and the button turned a quarter-revolution to bring the locking-lug D in line with the button-holes. The lug is now pressed 65 into the button-holes, when its higher portion, projecting entirely through the cuff, as shown, securely locks or prevents rotation of the button in the sleeve or cuff, and keeps the shoe at right angles with the button-holes, thus 70 preventing the button from unbuttoning and being lost.

To release the button from the cuff, it is only necessary to draw the lug D out of the button-holes by moving the head, as indicated by the 75 arrow in Fig. 3, and turning the button a quarter-revolution, when the shoe easily slips out of the cuff or sleeve.

Having thus described my invention, what I claim as new, and desire to secure by Letters 80 Patent, is—

A sleeve or cuff button composed of a head, A, central shank, B, shoe C, attached to the free end of said shank and extending on one side at, or nearly at, a right angle thereto, and 85 a locking-lug, D, attached to the head and extending from the foot of the shank on the side opposite to the shoe and at a right angle therewith, as and for the purpose specified.

In testimony whereof I affix my signature in 90 presence of two witnesses.

LEVI H. THOMAS.
